ISAAC B. SMITH AND HENRY C. BURR, OF SPRINGFIELD, VERMONT.

Letters Patent No. 82,168, dated September 15, 1868.

IMPROVEMENT IN HAMES.

The Schedule referred to in these Letters Patent and making part of the same.

TO ALL WHOM IT MAY CONCERN:

Be it known that we, ISAAC B. SMITH and HENRY C. BURR, of Springfield, Windsor county, State of Vermont, have invented certain new and useful Improvements in Hames; and we do hereby declare that the following is a full and clear description thereof, reference being had to the accompanying drawings, and to the letters of reference marked thereon.

In the drawings—

Figure 1 represents a side view, and

Figure 2 a bottom view of our improvements.

This invention consists of a new and useful arrangement of the staple for connecting the trace as well as the pole-strap ring to the hames.

The construction of this we will now describe. Posts A and B are set into the hames, at the usual position for the attachment of the trace, and these posts are provided with eyes, *a a* and *b*, through the ends of them, the eye *b* being furnished with screw-threads, for a purpose hereinafter described. It will be perceived that the post B is formed with two projections, C and D, making it a double post, with a space between them, the bottom part being formed solid, and curved at its inner face at *d*. Through the eyes of the posts is placed a bolt, E, which is provided at one end with a head, F, and at the other with a thread, G, which last engages with the threads in the eye *b*. When this post is screwed in, it joins the tops of the posts, and forms a double staple, with a place, H, for the trace-ring or catch, and a smaller place, I, for the pole-strap ring. Washers J and K are arranged so as to fit around the bolt between the posts, in order to prevent the chafing and wear of the metal as the rings of both trace and pole-strap play about.

The advantages of this device are that the main staple for the trace-ring is exempted from the wear and chafing of the pole-strap ring, and so also is the trace-ring, while the pole-strap ring, by being confined to a staple of its own, and yet in the same position as would be its place if occupying the main staple, is prevented from wearing the collar or trace either. The bolt allows them to be taken out and put back with ease and convenience, while the cylindrical washers upon the same prevent a great deal of wear. Besides this, the bolt-arrangement allows the hames to be used for different purposes; for instance, a hook can be put in the place used for the ordinary ring, converting the hames into a hook-hames, being in that capacity more applicable to cart-harness.

Now, having described our invention, what we claim as new, and desire to secure by Letters Patent, is—

1. The combination of the post A, double post B, and bolt E, arranged and constructed substantially as and for the purpose described.

2. In combination with the bolt E, the washers J and K, arranged upon it, substantially as set forth.

ISAAC B. SMITH,
HENRY C. BURR.
